UNITED STATES PATENT OFFICE.

MARY A. LOOS, OF PHILADELPHIA, PENNSYLVANIA.

FLOOR OIL-CLOTH.

SPECIFICATION forming part of Letters Patent No. 242,947, dated June 14, 1881.

Application filed May 13, 1881. (No model.)

To all whom it may concern:

Be it known that I, MARY A. Loos, a citizen of the United States, residing in Philadelphia, Pennsylvania, have invented an Improvement in Floor Oil-Cloths, of which the following is a specification.

The object of my invention is to prevent floor oil-cloth from adhering to the surface to which it is applied; and this object I attain by securing to the back of the oil-cloth a sheet of paper or equivalent material, all as hereinafter fully set forth.

In the accompanying drawings, Figure 1 is a perspective view of a sheet of ordinary floor oil-cloth provided with a backing in accordance with my invention, and Fig. 2 an exaggerated section of a portion of the same.

Ordinary floor oil-cloth, especially when freshly made, is of such a character that the pressure to which it is subjected when in use causes the back of the cloth to adhere to the floor or other surface to which it is applied, so that in removing the cloth not only is the latter likely to be torn, but the floor or other surface is rendered unsightly by the adhering patches, which interfere with the proper application of another covering.

In carrying out my invention I secure to the back of the strip or sheet of oil-cloth a sheet of paper of any desired thickness, the preference being given to thin paper on account of

the firmer adherence of the same to the oil-cloth and because of its cheapness. The paper may be applied to the oil-cloth by passing it with the latter between rolls, and thereby subjecting it to a pressure sufficient to cause it to adhere to the back of the cloth, or a suitable paste or cement may be applied to the paper or cloth to insure the firm attachment of the two. 35

I have found in practice that when the oil-cloth is thus backed pressure exerted upon the surface will not cause the back to adhere to the floor, the backing, moreover, causing no material difference in the weight or cost of the product. 40

Thin muslin or other cheap fabric may in some cases be substituted for the paper backing; but the latter is to be preferred, on account of its economy. 45

I claim as my invention—

As a new article of manufacture, floor oil-cloth having a backing of paper or equivalent material secured thereto, as and for the purpose herein set forth. 50

In testimony whereof I have signed my name to this specification in the presence of two subscribing witnesses. 55

MARY A. LOOS.
